UNITED STATES PATENT OFFICE.

CHARLES FRANCIS STRAUSBAUGH, OF DETROIT, MICHIGAN.

CONCRETE-WALL MOLD.

1,367,438.

Specification of Letters Patent.

Patented Feb. 1, 1921.

Application filed March 27, 1919. Serial No. 285,659.

To all whom it may concern:

Be it known that I, CHARLES FRANCIS STRAUSBAUGH, a citizen of the United States, residing at Detroit, in the county of Wayne 5 and State of Michigan, have invented certain new and useful Improvements in Concrete-Wall Molds, of which the following is a specification, reference being had therein to the accompanying drawings.

10 This invention relates to wall molds that may be used to form walls and other structures of concrete or other plastic material.

My invention aims to provide mold walls that may be assembled and maintained in proper alinement and spaced relation without any danger of the walls becoming accidentally displaced, and for this purpose I employ novel interlocking blocks and transverse members. The use of the blocks and 20 members does not interfere with the shape and design of the mold walls *per se*, and the mold may be built up as rapidly as a newly laid portion of wall is cured or seasoned.

25 The mechanical construction entering into my invention will be hereinafter specifically described and then claimed, and reference will now be had to the drawing, wherein—

30 Figure 1 is a perspective view of parts of the mold assembled, and the mold filled with concrete or other plastic material;

Fig. 2 is a similar view showing a portion of a wall with some of the mold parts removed therefrom;

Fig. 3 is a perspective view of a portion of a mold wall;

Fig. 4 is an enlarged perspective view of a portion of mold walls showing a connecting member therefor;

Fig. 5 is a perspective view of a detached connecting member;

Fig. 6 is a perspective view of interlocked mold blocks showing the outer face thereof;

45 Fig. 7 is a similar view showing the inner faces of the block;

Fig. 8 is a plan of a modified form of connecting member such as may be used at the juncture or angle of two walls;

50 Fig. 9 is a perspective view of an angular tie block;

Fig. 10 is a similar view of interlocked blocks with the tie block designed for an offset mold wall;

55 Fig. 11 is a similar view showing the manner in which a tie block enters wall blocks;

Fig. 12 is a perspective view of a modified form of angular tie block;

Fig. 13 is a similar view of a curved tie block;

60 Fig. 14 shows views in perspective of wall blocks to which a single tie block may be connected;

Fig. 15 is a side elevation of a screw or bolt adapted for fastening a wall block to 65 a mold wall plate;

Fig. 16 shows views of a nut or socket for the screw or bolt; and

Fig. 17 is a perspective view of a modified form of wall block.

70 In the accompanying drawings, the reference numeral 2 denotes mold wall plates and each plate is substantially rectangular in elevation and of sufficient thickness to permit of said plates being placed in superposed relation adjoining one another so as to form a mold wall. With two such walls in spaced relation the intervening space may be filled with concrete 1 or other plastic material.

75 Each mold wall plate 2 has its upper edges, at its ends provided with notches or recesses 8 and when the mold wall plates are placed in abutting assembled relation the recesses coöperate in forming transverse 80 grooves or openings and the grooves or openings of one mold wall are adapted to transversely aline with the grooves or openings of the other mold wall.

85 Each mold wall plate may have its outer 90 face provided with blocks 22 and these blocks are preferably placed at the upper and lower edges of the plate, adjacent the ends thereof so that the blocks of one plate will vertically aline with the blocks of an adjoining plate, and the blocks at the edges of the adjoining plates abut each other or approximately so, whereby such blocks may be connected by a tie block 14. Each of the 95 blocks 22 has a tapered dovetailed tongue 24 with the tongue disposed in a vertical plane intermediate the side edges of each block and the tongue tapers inwardly toward the upper edge of a block so that it will be necessary to place the tie block 14 on the 100 upper end of the tongue and then shift said tie block downwardly to connect the mold blocks. The tongues of the mold blocks at the upper edge of each mold plate are 105 slightly larger than the tongues of the blocks at the lower edge of the mold plate so that when the mold plates are placed in

superposed relation the tongues at the upper edge of the mold plate will represent a continuation of the tongues at the lower edge of the adjacent mold plate. This will permit of the tie plate 14 being placed downwardly over the tongue 24 to connect all of the contiguous blocks, and in order that the tie plate 14 may be employed for this purpose, said tie plate has its inner face provided with tapered dovetailed grooves 21^A. Each tie block is of a sufficient area to practically interlock four of the mold blocks 22 and to connect the mold blocks to the outer faces of the mold plates 2 I prefer to use screws or bolts 6 and nuts or sockets 2^A, both of which are shown in Figs. 15 and 16.

The bolt or screw 6 has a head 3^A adapted to be countersunk in the inner wall of the mold wall plate 2, and the socket 2^A has a nut portion 5^A adapted to be countersunk in the mold blocks 22, so that the connecting means between the mold wall plates and the blocks will be flush therewith. With the sockets 2^A permanently located in the blocks 22 the screw 6 may detachably support said blocks and should a block be injured it may be readily removed.

Each tie block 14 has its lower edge provided with a transverse notch 19 adapted to register with the recesses 8 of the mold wall plates 2, so that said tie blocks may fit over transverse connecting members 10 which are placed in the recesses 8 of the mold walls as the mold is built up. These connecting members are best shown in Figs. 1, 4 and 5 and each member is in the form of a bar that may be seated in the recesses 8 and extend from between the blocks 22 at the upper edges of adjoining mold wall plates. The side walls of each connecting member, at its ends, are provided with vertical grooves 7, and each groove may have its walls tapered or beveled to correspond to the taper or bevel of the walls of the notches 19, so that each tie plate may be fitted down over the connecting member and become interlocked therewith, thus binding the wall plate blocks 22 and the tie blocks 10 to the connecting members which will prevent lateral displacement or bulging of the mold wall plates when assembled as a mold.

As shown in Fig. 5 each connecting member may have its ends provided with additional grooves 7 and such grooves will serve two purposes. First, the mold walls may be placed a greater distance apart should a wider wall be desired, or devices may be anchored on the ends of the connecting members to facilitate assembling the mold parts, such devices forming no part of this invention.

Considering Fig. 1, it will be noted that the mold walls are tied together by the con-

necting members 10 and when walls are to be formed at an angle to one another I may use angular or curved tie blocks. An angular tie block 9 is shown in Fig. 9 and besides having its inner face provided with dovetailed grooves it has a notch 7^A to receive the connecting member, and it is obvious that the recesses 8 will have the walls thereof beveled to align with the walls of the notch 7^A to permit of the connecting member extending in an angular direction relative to adjacent connecting members in the same lateral plane. This is best shown at the left hand side of Fig. 1, where the walls form an L. When the walls form a T, some of the connecting members 10 may have angular ends so that angle tie blocks 9 may be placed in engagement therewith.

A curved tie block 9^A is shown in Fig. 13, and in constructing some concrete walls or curbings, it may be possible to provide a connecting member 40 with an angle tie block 9 and a triangular tie block 41, especially when a portion of a wall or curbing is disposed at an acute angle relative to an adjoining wall or curb portion.

Since some walls may have offset portions, tie blocks 23^A may be employed as shown in Fig. 10 where one part of the block is of greater thickness than another part. This view of the drawing also shows that a tie block may have a tongue 24 at one end thereof and a groove 21^A at the opposite end thereof, and the same is shown in connection with the angular tie block of Fig. 12, it being understood that mold blocks will be used having tongues to engage in the grooves 21^A of the tie blocks. Such tongued mold blocks have been shown in Fig. 14 and designated 4. The mold block 4 may also have the inner faces thereof beveled or inclined and the tie blocks employed to interlock the mold blocks will be similarly formed, as brought out in Fig. 7, whereby the tie blocks will have a wedging action tending to tighten the mold blocks relative to the connecting members.

Since the mold wall plates may be of considerable length it may be necessary to use connecting members intermediate the ends thereof and such long mold plates are designated 26 in Fig. 2, and have the upper and lower edges thereof provided with single long blocks 21 which are used in lieu of two small mold blocks as at the adjoining edges of mold plates.

In some constructions it may be necessary for the mold blocks at the upper edges of mold plates to extend on to the lower edges of superposed wall plates, as shown in Fig. 4 and thus provide braces or guides for the upper mold wall plates when assembling the same. Then again, it is possible to use the long blocks 21 even at the junc-

ture of a plurality of mold plates. It is in this connection that I do not care to limit myself to the precise size or shape of the mold wall blocks or even the tie blocks 5 since different kinds of concrete walls will require different kinds of molds.

It is obvious that the inner faces of the mold wall plates may be finished to impart a desired finish to the exterior surfaces of 10 the wall, and after the parts of the mold have been removed the openings left by the connecting members may be plugged with concrete or otherwise closed.

What I claim is:—

15 1. The combination of mold plates adapted to be placed in superposed relation to form opposed mold walls, mold blocks carried by said plates at adjacent edges thereof, connecting members extending from one 20 mold wall to the other with the ends of said connecting members at said mold blocks, and tie blocks fitting on said mold blocks and said connecting members and holding adjacent mold blocks relative to said connecting members.

25 2. The combination set forth in claim 1, wherein the mold and tie blocks having tongue and groove connections and said tie

blocks are held against longitudinal displacement on said connecting members. 30

3. The combination of mold plates adapted to be placed in superposed abutting relation to form opposed mold walls, said mold plates having the upper edges thereof recessed, mold blocks on said mold plates at 35 the abutting edges thereof, connecting members extending from one mold wall to the other and protruding from said mold walls, said connecting members being seated in the recesses of said mold plates, and tie 40 blocks fitted on said mold blocks and having the lower edges thereof notched to receive said connecting members, so that said mold and tie blocks are held against displacement relative to said connecting members. 45

4. The combination set forth in claim 3, wherein said mold and tie blocks have tongue and groove connections.

In testimony whereof I affix my signature 50 in presence of two witnesses.

CHARLES FRANCIS STRAUSBAUGH.
